(57) **CLAIM**

The ornamental design for a medical device connector, as shown and described.

DESCRIPTION

FIG. 1 is a top plan view of the medical device connector;
FIG. 2 is a front elevation view of the medical device connector, the rear, left side and right side elevation views being the same;

FIG. 3 is a bottom plan view of the medical device connector; and,

FIG. 4 is a perspective view of the medical device connector. The features of the article shown in broken lines illustrate the environment in which the claimed design is applied and form no part thereof.
